UNITED STATES PATENT OFFICE.

GEORGE O. SANBORN, OF SEATTLE, WASHINGTON.

DESIGN FOR A NECKTIE.

No. 38,914.

Specification for Design.

Patented Nov. 26, 1907.

Application filed October 17, 1906. Serial No. 339,421. Term of patent 3½ years.

To all whom it may concern:

Be it known that I, GEORGE O. SANBORN, a citizen of the United States, residing at Seattle, in the county of King and State of Washington, have invented a new, original, and ornamental Design for a Necktie, of which the following is a specification, reference being had therein to the accompanying drawing, forming a part thereof.

The figure is a perspective view of a necktie showing the design.

I claim:

The ornamental design for a necktie as shown.

GEORGE O. SANBORN.
